UNITED STATES PATENT OFFICE.

LEVI W. STOCKWELL, OF CLEVELAND, OHIO, ASSIGNOR TO WILLIAM H. PRICE, OF SAME PLACE.

SCREW-PLATE.

SPECIFICATION forming part of Letters Patent No. 249,860, dated November 22, 1881.

Application filed April 1, 1881. (No model.)

To all whom it may concern:

Be it known that I, LEVI W. STOCKWELL, of Cleveland, Ohio, have invented a new and useful Improvement in Screw-Plates, of which 5 the following is a specification.

My invention relates to that class of screw-plates in which the threading-dies are adjusted and moved in radial grooves toward and from the center of the plate by means of a disk provided on one side with eccentric cams which enter slots across the dies.

The object of my invention is to provide the cam-disk with eccentric cams of unequal lengths, one for each threading-die, and so arranged that all the dies may be placed in the radial grooves of the plate, and then, by turning the cam-disk, the cams will severally enter, one at a time, the slots across the dies. By reason of the cams being of unequal lengths each die may 20 be adjusted to a position for its cam to enter it without risk of dislodging such of the other dies as may have already been adjusted and entered by their respective cams.

Another object of my invention is to hold the 25 cam-disk in position, when the dies have been properly adjusted for operation, by means of an adjustable slotted stop attached to the side of the screw-plate by a screw through the slot, the stop being provided with a projection which 30 enters a notch in the circumference of the cam-disk.

In the drawings, Figure 1 is an elevation. Fig. 2 is a vertical section. Fig. 3 is a plan 35 representing the cam-disk as having a small portion of it broken away. Fig. 4 is a horizontal section at the line $x-x$ in Fig. 2.

The screw-plate is operated by means of handles h on opposite sides of the frame. The dies a are in radial grooves in frame b , and 40 have notches or grooves a' across them. Cam-disk d is provided with eccentric cams c c' c^2 c^3 projecting from one side of the disk. These cams enter grooves a' in the dies a . Cam-disk d is placed against the open end of frame b , 45 with its cams c c' c^2 c^3 in the circular grooves b' in the frame, where it is retained by the face-plate a^2 , which is attached by screws to frame b . The cam-disk d is held loosely against the frame, so that it may be turned. It is provided with

a handle, d' , by means of which it may be turned 50 on the frame to move the dies a toward and from the center of the screw-plate. Its diameter is greater than that of frame b , and its circumference is notched at x to receive the projection e of stop s . The spring-stop s is attached to the circumference of frame b by 55 screw o and thumb-nut o' , and is adjustable by means of its slot n . It is a spring, in order that its projection e may be withdrawn from notch x without loosening thumb-screw o' . Its function is to hold cam-disk d in place when the dies are in proper position for threading. When the threading has been completed the dies a may be withdrawn to release the threaded bolt by drawing back the end of the spring- 60 stop s till its projection e is out of notch x , and then turning cam-disk d by its handle d' . When the threaded bolt has been withdrawn another bolt to be threaded may be substituted and dies a closed against it without readjustment 65 by turning cam-disk d till the projection e of stop s springs into notch x .

To adjust dies a to different-sized bolts to be threaded, thumb-nut o' should be loosened and cam-disk d turned, carrying with it stop s till 75 the dies a are properly adjusted, when thumb-nut o' may be tightened, and then the screw-plate is again ready for operation.

The cams c c' c^2 c^3 are of unequal length, cam c being the longest, and each of the others, in 80 order, being of gradually decreased length.

When it is desired to remove the dies and replace them cam-disk d should be turned to such a position that all the dies a will be dislodged from the cams, when they may be withdrawn from frame b between the ends of the cams. When dies a have been replaced in the frame between the ends of the cams the cam-disk d should be turned until the outer end of cam c is in contact with the side of the die, 85 which may then be moved radially by hand until, by slightly pressing on the handle d' of cam-disk d , the cam c enters the notch a' in the die, and the outer end of cam c' is in contact with the side of the next die. Then, in the 90 same manner as just described, cam c' may be caused to enter the notch in its die without dislodging the die from cam c . In this manner 95

all of the cams successively may be caused to enter the notches a' in dies a without any of them becoming dislodged during the operation.

In the relative positions of the cams and dies 5 as shown in Fig. 4, all the dies having first been placed in their radial grooves in frame b between the ends of the cams c c' c^2 c^3 , and the cam-disk d turned till cams c c' successively entered their dies, as above described, the operator may now successively adjust the remaining two dies to be entered by their cams c^2 c^3 without either of the other dies becoming dislodged from its cam.

I claim as my invention—

15 1. In a screw-plate, the dies a , having notches

a' , in combination with a cam-disk, d , provided with eccentric cams in such relative positions to the dies that by turning the cam-disk they will successively enter the dies, substantially as described.

20

2. The combination of notched dies a with eccentric cams c c' , of unequal length, substantially as described.

3. The dies a and cam-disk d , having the notch x , in combination with the adjustable 25 spring-stop s , substantially as described.

LEVI W. STOCKWELL.
